CLAIM

The ornamental design for a cigarette lighter, as shown and described.

DESCRIPTION

FIG. 1 is a front, top perspective view of a cigarette lighter, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the cigarette lighter, shown in alternate configuration of use.

The broken lines in the figures illustrate portions of the cigarette lighter that form no part of the claimed design.
